(57) **CLAIM**

The ornamental design for a quad light channel, as shown and described.

DESCRIPTION

FIG. 1 is an isolated perspective view of the quad light channel, showing the new design;

FIG. 2 is a front elevational view of quad light channel thereof;

FIG. 3 is a rear elevational view of the quad light channel thereof;

FIG. 4 is a left side elevational view of the quad light channel thereof;

FIG. 5 is a right side elevational view of the quad light channel thereof;

FIG. 6 is a top plan view of the quad light channel thereof, FIG. 7 is a bottom plan view of the quad light channel thereof; and,

FIG. 8 is an environmental perspective view of the quad light channel thereof.

In the drawings, the broken lines show portions of a quad light channel that form no part of the claim.
